HAIR COMB

Michael Liguori, Lodi, N. Y.

Application June 12, 1935, Serial No. 26,178

3 Claims. (Cl. 132—15)

This invention relates to new and useful improvements in a hair comb.

The invention has for an object the construction of a device as mentioned which is characterized by a flat casing and a comb support slidably mounted therein and extendable therefrom, and a novel arrangement for supporting a comb on said comb support.

Still further the invention proposes the provision of resilient means within the casing acting against the comb support for normally extending the latter element, and restrainable with a manually operated catch.

As a further object of this invention a novel provision is made for releasably holding the comb upon the comb support and arranged in such fashion as to be automatically operable when the comb support is forced to its retracted position.

Another object of the invention is the construction of an article as described which is simple and durable and which can be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

Fig. 1 is a perspective view of a device constructed according to this invention, illustrated with the comb retracted.

Fig. 2 is a longitudinal sectional view of the device illustrated with the comb extended.

Fig. 3 is an elevational view looking in the direction of the line 3—3 of Fig. 2.

Fig. 4 is a fragmentary enlarged sectional view taken on the line 4—4 of Fig. 2.

Fig. 5 is a fragmentary sectional view taken on the line 5—5 of Fig. 4.

Fig. 6 is a similar view to Fig. 1, but showing a modified form of the invention.

The hair comb, according to this invention, comprises a frame casing 10 with an open end 10'. A comb support 11 is slidably mounted within the casing and is adapted to be extended from the open end 10'. Resilient means in the form of a spring 12 is arranged within the casing and acts between the comb support and the rear of the casing for normally extending the comb. A catch 13 is provided for normally holding the comb support in its retracted position. A comb 14 is mounted upon the comb support and is adapted to be housed within the casing 10 when

the latter is retracted, and to be extended from the casing when the comb support is in its extended position.

The casing 10 has a small side compartment 10^{aa} in which the catch 13 is housed. The catch 13 comprises a catch element 13^a pivotally mounted intermediate of its ends at the point 13^b. The element 13^a has its rear end 13^c extended through an opening in the compartment 10^{aa} by which it may be manually moved. A spring 13^d acts 10 against the catch element so as to normally urge the front end 13^e thereof into operative position. This front end is adapted to engage a cut-out portion 11^a in the comb support 11 to hold the latter element in the retracted position. 15

The comb support 11 comprises an inverted U-shaped arm 11^b connected with a base block 11^c. The base block is of a shape so as to conform with the interior of the casing 10 and so slidably support the comb support. The spring 12 is of the spiral type and has one end thereof engaged upon a peg 15 mounted on the rear of the casing 10, and has its other end engaged within a recess 11^d formed in the inner end of the comb support. 20

The side walls of the casing 10 are formed with longitudinal bulged portions 10^e to accommodate the spring 12. The spring 12 is restrained from completely ejecting the comb support by reason of small flanges 10^b upon the open end 10' of the casing. These small flanges 10^b are adapted to restrain the base 11^c of the comb support from being ejected. A pad 17 is mounted across the front of the base block 11^c of the comb support so as to reduce to a minimum the noise 30 when the base block 11^c strikes the flanges 10^b during the extension of the comb. 35

The comb 14 is formed with longitudinal grooves 14^a on the sides thereof. The free edges of the U-shaped arm portion 11^b of the comb support are turned inwards so as to engage these grooves to slidably support the comb. The comb may be removed from the U-shaped arm merely by sliding it from the front thereof. Thus, when the teeth of the comb break, a new one may be 40 substituted. 45

A means is provided for releasably holding the comb on the comb support. This means comprises a keeper 20 having a portion of its rear edge formed into a coil 20^a engaged by a pintle 21 cooperating with a complementary coil upon the material of the arm 11^b for hingedly supporting the keeper element. The keeper element is adapted to be engaged within an opening 22 formed in the side of the U-shaped arm. The 50 55

keeper element 20 is provided with a front lip 23 at right angles to the main portion thereof which extends into the space between the sides of the U-shaped arm and into a transverse groove 14^c formed in the back edge of the comb to prevent the comb from moving longitudinally. The lip 23 is provided with an offset portion 23' co-actable with a complementary offset portion on a finger 24 stamped from the material of the U-shaped arm on the opposite side to the side on which the keeper 20 is located.

The keeper 20 may be manually opened by inserting a penknife or other small implement beneath an edge thereof and pivoting it outwards against the restraining action of the finger 24. The comb 14 may then be removed from the comb support. The same comb, or a new comb, may be placed upon the comb support and when the latter element is forced to its retracted position the keeper 20 (which is now open) will strike against the edge 10^e of the casing 10 which will automatically force it into its closed position. If the comb 14 is not properly inserted in position it will be impossible to move the comb support inwards. It is therefore necessary for an operator to properly adjust the comb on the support. Once the keeper 20 is forced into the closed position it will be maintained in this position by the finger 24.

The device is illustrated in Fig. 2 with the comb extended. In this condition it may be used for combing purposes. The comb may be forced to the retracted position by merely forcing the comb support inwards to a position in which the catch 13 will engage the cutout 11^a. The device is then in the condition shown in Fig. 1. The comb may be extended whenever desired by merely pressing the end 13^e of the catch element.

The device illustrated in Fig. 6 shows a catch 13' secured pivotally to the outside of the casing 10 at 13^b. The front end 13^e of the catch is passing through an opening 10^c and is adapted to engage the cutout portion 11^a in the comb support 11 as previously described. The spring 45 13^f is integral with catch 13' and tends to normally urge the front end 13^e into operative position.

While I have illustrated and described the preferred embodiment of my invention, it is to be understood that I do not limit myself to the precise construction herein disclosed and the right is reserved to all changes and modifications

coming within the scope of the invention as defined in the appended claims.

Having thus described my invention, what I claim as new, and desire to secure by United States Letters Patent is:—

1. A tonsorial device comprising a flat casing with an open end, a catch member on the said casing, inwardly extending flanges on the open end of the casing, a comb support arranged for reciprocation into and out of said casing consisting of a flange-abutting base block and an arm having a catch-engaging notch in the outer end, a comb rigidly mounted on said comb support, a normally compressed spring housed within said casing between the inner end of said comb support and the closed end of said casing, said catch being normally engaged in said notch, said spring being adapted to urge said comb out of said casing and retain the same in such position while said comb is being used.

2. A tonsorial device substantially as described in claim 1, said arm being substantially U-shaped in cross section and having portions of the stems bent toward each other, said comb having longitudinal grooves and being disposed between said stems, said inwardly bent portions being disposed within said grooves.

3. A tonsorial device comprising a flat casing with an open end, a catch member on the said casing, inwardly extending flanges on the open end of the casing, a comb support arranged for reciprocation into and out of said casing consisting of a flange-abutting base block and an arm having a catch-engaging notch in the outer end, a comb rigidly mounted on said comb support, a normally compressed spring housed within said casing between the inner end of said comb support and the closed end of said casing, said catch being normally engaged in said notch, said spring being adapted to urge said comb out of said casing and retain the same in such position while said comb is being used, said arm being substantially U-shaped in cross section and having portions of the stems bent toward each other, said comb having longitudinal grooves and being disposed between said stems, said inwardly bent portions being disposed within said grooves, and displaceable means disposed within said arm and cooperable with said comb to prevent said comb from moving longitudinally with respect to said arm.

MICHAEL LIGUORI.
